UNITED STATES PATENT OFFICE

116,772

DESIGN FOR A DRESS

Maurice Extract, New York, N. Y.

Application August 21, 1939, Serial No. 86,794

Term of patent 3½ years

To all whom it may concern:

Be it known that I, Maurice Extract, a citizen of the United States, residing in New York city, in the county of New York and State of New York, have invented a new, original, and ornamental Design for a Dress, of which the following is a specification, reference being had to the accompanying drawings, forming part thereof.

Fig. 1 is a front view of a dress showing my design.

Fig. 2 is a rear view of Fig. 1, and
Fig. 3 is the side view thereof.

I claim:

The ornamental design for a dress, substantially as shown.

MAURICE EXTRACT.
